UNITED STATES PATENT OFFICE.

WILLIAM KIRKUP, OF CINCINNATI, OHIO.

IMPROVEMENT IN GLOBE-VALVES.

Specification forming part of Letters Patent No. 132,471, dated October 22, 1872.

To all whom it may concern:

Be it known that I, WILLIAM KIRKUP, of Cincinnati, Hamilton county, Ohio, have invented an Improvement in Globe-Valves, of which the following is a specification:

Nature and Objects of the Invention.

My invention relates to a peculiar construction of a "globe-valve," whereby the conical valve which forms a part of this class of cocks may, after becoming worn and leaky, be reground upon its seat without removing the cock from its place; and my invention consists in the provision of a gland or guide ring, which, occupying a counter-bore in the cock-neck and fitting around the outer periphery of the stem-thread, serves, after the nut has been unscrewed from the stem-thread, to guide the stem during the operation of regrinding.

General Description.

Figure 1 is partially sectional elevation of a "globe-valve" embodying my invention, the parts being in condition for regrinding. Fig. 2 shows my valve and valve-stem with its guide-collar.

A represents the "globe" or valve chamber, having a customary valve-seat, B. C is the neck of the valve-chamber, having its inside smooth and provided with a counter-bore, D, to receive a gland or collar, E, whose orifice e snugly encircles the periphery of the thread f of the valve-stem F. The threaded portion

f of the valve-stem occupies the threaded orifice g of nut G, whose lower end is counter-bored and screw-threaded, g', to screw down upon the exteriorly-threaded neck C. H are guide-wings on the bottom of the conical valve I, which wings occupy and fit snugly within the cylindrical aperture J of the valve-seat. K is the cap of customary stuffing-box.

Operation.

To regrind the valve the nut G is unscrewed from the neck, as shown in Fig. 1. The stem may then be rotated to and fro by means of its handle, the gland, meanwhile, holding it erect. The valve having, by this means, been ground true, is restored to its working condition by simply screwing down the nut G.

Claim.

I claim as new and of my invention.

The guide-wings H below the valve I, and the guide-ring E surrounding the threaded neck f of the valve-stem, in combination with the said valve I and with the sockets D and J, all constructed and arranged as and for the purposes specified.

In testimony of which invention I hereunto set my hand.

WM. KIRKUP.
